UNITED STATES PATENT OFFICE.

PHILIP O. HARDING, OF RANCAGUA, CHILE.

MACHINERY FOR AGGLOMERATING ORE.

1,239,179.

Specification of Letters Patent.

Patented Sept. 4, 1917.

Application filed January 15, 1917. Serial No. 142,449.

To all whom it may concern:

Be it known that I, PHILIP O. HARDING, residing at Rancagua, in the Republic of Chile, a citizen of the United States, have 5 invented or discovered certain new and useful Improvements in Machinery for Agglomerating Ore, of which improvements the following is a specification.

My invention relates to improvements in 10 machinery for agglomerating ore, and such like agglomerable finely divided material; more specifically, it consists in improvements in the agglomerating machine which is described in Letters Patent of the United 15 States No. 1,166,904, granted me January 4, 1916.

The improved machine of my present invention is shown in the accompanying drawings. Figure 1 is a view of the machine in 20 vertical medial section; Fig. 2 is a fragmentary view in horizontal section, the plane of section being that indicated by the line II—II, Fig. 1. Fig. 3 is a fragmentary view in horizontal section, the plane of section being that indicated by the line 25 III—III, Fig. 1. Fig. 4 is a fragmentary view corresponding to Fig. 1 and showing a modification in detail. Fig. 5 is a view in horizontal section on the plane indicated by 30 the line V—V, Fig. 4. Figs. 6—9, inclusive, show successively, in medial vertical section and in plan, further modifications in the shape of the feed hopper shown in Figs. 4 and 5. Fig. 10 is like Fig. 2 but shows a 35 modification of the feed apparatus.

The essential parts of the machine are the same as in the machine of Fig. 1 of the patent mentioned. They include a vertically arranged agglomeration chamber or tube 1, 40 terminating in a downwardly flaring bell or mouth 27. Beneath and opposite the mouth of the tube is the breaker 3. The upper end of the tube is inclosed by the walls of a substantially air-tight chamber 5, from 45 which a suction pipe 4 leads. A feed mechanism, such as not seriously to interfere with the upwardly maintained draft through tube 1, is exemplified in the feed pipe 7, through which material is advanced by a 50 suitably driven feed screw from an external hopper and from which the material falls to the upper intake end of tube 1. A spreader and pusher 8 (detailed illustration of which will be found in the patent referred 55 to) is arranged in the upper portion of tube 1. It is carried by and rotated by a suitably

driven shaft 10. The shaft 10 and the spreader which it carries are vertically reciprocable, as is suggested by the connection shown at 11, Fig. 1, and more fully shown 60 in the patent mentioned.

The operation is preferably continuous. Material fed through feed pipe 7 descends by gravity into and fills tube 1, the newly entering material resting on the material in 65 course of treatment, and the whole mass resting on breaker 3 below. Combustion of the material within tube 1 is produced either by externally applied or internally developed heat and is preferably concentrated at 70 a level or zone in the upper portion of the tube. This also is made plain in the specification of my earlier patent mentioned above. Rotation of the breaker, upon which the charge of material under treatment 75 rests, effects a breaking up of the agglomerated mass as it descends from the region of combustion, and at the same time effects the escape of the broken-up material peripherally around the breaker and between it and 80 the rim of the bell-shaped mouth 27 of the tube. During the operation a draft of combustion-sustaining air (or other gas), drawn by suction-tube 4, sweeps in through tube 1, and carries upward and back into the region 85 of combustion such friable material as, first pocketed in the agglomerated material, has subsequently been released by the fragmentation of the body of material descending in the tube from the region of combustion. 90

My present invention particularly concerns the feeding in of friable material at the top of the sintering tube 1.

The feed apparatus, which in Fig. 1 consists of the tube 7 with its contained conveying worm, terminates inwardly in a delivery portion, a lip made preferably as a separable structural part, that it may be removed, shaped, and replaced as desired. Comparison of Figs. 1 and 2 will show the 95 particular arrangement and shaping of this delivery portion in which my invention partially consists. The delivery opening *a a* is arranged directly above the intake end of tube 1 and extends from a point near the 100 prolonged vertical axis of the tube, radially to a point above the periphery of the tube, and the opening is of gradually increasing width from axis to periphery (using terms which indicate its relation to the tube). The 105 reason for such gradation in width is that the best distribution of material as it enters

the tube may be had, and the least redistribution of material by spreader 8 required. The material is fed in smallest quantities to the central portions of the intake end of the tube and in largest quantities to the peripheral portions, where larger quantities are needed.

The best shaping of the delivery orifice will in any given case be dependent on the character of the infed material; some material will advantageously be fed from a less, some from a more gradually tapered opening, to effect the desired evenness of spreading. Accordingly, in each particular installation the orifice may be cut and shaped as experience shall indicate. The orifice may be strengthened against deformation while in service by interrupting and strengthening cross bars, as the drawings indicate. This may be merely a portion of the material of which the discharge end of the tube is made, which has not been cut away.

In successive working with materials of different characteristics, one delivery end of tube 7 may be replaced by another with a differently proportional delivery orifice.

In order to effect the circumferential distribution of the material fed in through conduit 7 around the entire circle of the intake end of tube 1, I interpose between the delivery end of conduit 7 and the intake end of tube 1 the feed-chute 22. This chute is helically shaped, and is rigidly mounted on and carried by the shaft 10. It extends through one complete helical convolution though preferably no more than that. Throughout all the range of its rotation it extends beneath and receives material descending from the delivery orifice of the feed conduit, and by its rotation it is constantly spreading in the mouth of tube 1 the material which it so receives. The shape of this helical chute in cross section is relatively unimportant, but a serviceable shape is indicated in Fig. 1, where it is shown to be a flat-bottomed trough with side flanges, and with a medial directing flange also.

Figs. 4 and 5 show a modification in this, that the feed conduit 7 discharges material into a hopper 23 carried by shaft 10, and this hopper has a delivery orifice *b* radially arranged with respect to the intake of the tube 1 below and tapered, as the orifice *a* of the delivery end 21 of the conduit of Figs. 1 and 2 is tapered.

Figs. 6-9, inclusive, show that this feed hopper may be modified in shape in various ways. Figs. 6 and 7 show the hopper 23^a to be provided with vertical side walls and a uniformly inclined bottom in which the radially extending tapered orifice *c* is formed; Figs. 8 and 9 indicate that the hopper 23^b may be provided (as chute 22 of Figs. 1 and 2 is provided) with an intermediate flange 28, keeping separate the ma-

terial fed to the central portion of the tube from that fed to the peripheral portion. It will be understood that the hopper of Figs. 6-9 may be combined with a feed conduit such as that shown in Figs. 1 and 2, taking the place of the feed chute 22 of Fig. 1. When so combined, the tapered delivery orifice of the conduit will already have effected that radial distribution of the fed-in material which has already been mentioned, and, accordingly, there is not the same necessity for tapering the orifice of the hopper also. Nevertheless, the orifice in the hopper may in any case be tapered. As indicated in Fig. 9, however, the hopper 23^b though provided with a medial flange 28, has an untapered orifice *d*. It will be understood that, combined with the feed conduit of Fig. 1, the medial flange of this hopper will maintain to a degree the distribution effected by the tapered orifice of the conduit 7.

As shown in Fig. 10, the delivery lip of the feed conduit may be modified. The longitudinal strengthening bar is indeed a partition which cuts and divides the advancing stream of in-fed material into two streams. The two portions of the orifice are arranged, one substantially on one side, the other substantially on the other side of this partition. (The dotted lines, however, indicate that each of these openings may extend somewhat beyond the dividing partition.) The two openings are arranged in sequence longitudinally of the feed conduit and one of them (the one first encountered by the advancing material) is larger than the other. (They may, as in Fig. 2, be tapered longitudinally.) The effect is that the oncoming stream of in-fed material is divided into two streams, one of which flows in greater volume to the peripheral portion of the tubular furnace chamber below, and the other in less volume to the central portion.

The features of construction of the breaker, arranged opposite the lower end of the sintering tube, are shown in Figs. 1 and 3. The breaker 3 is preferably of the spherical contour here indicated, rather than conical, and it is preferably imperforate. It is provided underneath with an open-ended sleeve 24 which idly engages a stub-shaft 25. Stub 25 constitutes the eccentrically placed hub or stud of a disk 26, suitably mounted and driven. Manifestly, the rotation of the disk causes the breaker to revolve in its position opposite the discharge end of tube 1. At the same time the breaker is free to rotate idly on shaft 25. I use the terms revolve and rotate with precision of meaning; the breaker revolves about the prolonged axis of the sintering chamber, it rotates on its supporting shaft.

The breaker 3 is preferably imperforate, and the flaring bell-shaped extension 27 of the tube 1 may, as indicated in Fig. 1, be

shaped with bars and intervening longitudinally extending slots, after the manner of a grate.

The operation is in general features the same as in the machine of my earlier patent mentioned above. The refinements upon that operation which are achieved by my present invention concern the progress of the material through the sintering tube; the end in view being evenness and regularity of operation. To this end the material entering the tube 1 at the intake end is radially distributed and circumferentially spread to afford uniformity of feed over the area of the intake, or at least the best distribution to meet the conditions of combustion; and, further, the breaking up of the agglomerated material and the freedom of its discharge is more effectually attained. The feeding mechanism so distributes the material as it enters the sintering tube as to prevent uneven packing; thus the formation of channels is avoided through which the up-flowing gases might otherwise pass. At the same time the rotary and revoluble breaker is effective to break the descending sintered material into small lumps, with the result that the material descends in the tube more gradually, and undesirable slips are prevented.

I claim as my invention:

1. In a sintering machine, the combination of a vertically disposed tubular sintering chamber, of a conveyer arranged above said chamber and provided with a tapered delivery orifice radially arranged and stationary with respect to said chamber, and a spreader arranged beneath said conveyer.

Copies of this patent may be obtained for five cents each, by addressing the "Commissioner of Patents, Washington, D. C."

2. In a sintering machine, the combination with a vertically disposed tubular sintering chamber of a feed mechanism provided with a tapered delivery orifice arranged above said chamber and radially with respect thereto and at an interval therefrom, and a rotary helical chute arranged between the delivery orifice of said feed mechanism and the upper end of said sintering chamber.

3. In a sintering machine, the combination with a vertically disposed tubular sintering chamber of a feed mechanism provided with a tapered delivery orifice arranged above said chamber and radially with respect thereto and at an interval therefrom, and a rotary chute arranged between the delivery orifice of said feed mechanism and the upper end of said sintering chamber.

4. In a sintering machine, the combination with a vertically disposed tubular sintering chamber of a feed mechanism provided with a tapered delivery orifice arranged above said chamber and radially with respect thereto and at an interval therefrom, and a rotary helical chute arranged between the delivery orifice of said feed mechanism and the upper end of said sintering chamber, said chute being provided intermediate its width with a directing flange.

In testimony whereof I have hereunto set my hand.

PHILIP O. HARDING.
